UNITED STATES PATENT OFFICE.

RICHARD TOENNES, OF BOONVILLE, MISSOURI.

SMOKE-RING BLOWER.

Application filed February 23, 1921. Serial No. 447,158.

To all whom it may concern:

Be it known that I, RICHARD TOENNES, a citizen of the United States, residing at Boonville, in the county of Cooper and State 5 of Missouri, have invented certain new and useful Improvements in Smoke-Ring Blowers, of which the following is a specification.

This invention relates to improvements in smoke-ring blowers and has for its particular object to provide a toy of this character which is amusing and entertaining to both old and young folks, and which is simple in construction and inexpensive to manufacture, so that it can be made in large quantities and be used as an advertising medium by dealers in merchandise of different varieties.

A further object of the invention is to provide a toy of this character wherein the parts 20 are separable and of a shape which can be nested so that they can be shipped in quantities without danger of being mashed or cracked.

These and other objects hereinafter set 25 forth are attained by the means illustrated in the accompanying drawing, in which:—

Fig. 1, is a perspective view of one of the blowers. Fig. 2, is a longitudinal sectional view of the form shown in Fig. 1. Fig. 3, 30 is a view similar to Fig. 2, showing the mouth-piece insert in an opposite end from that shown in Fig. 1. Fig. 4, is a sectional view showing a modified form of the device. Fig. 5, is a side elevation partially in section showing a further modified form, and 35 Fig. 6 shows another form.

Similar reference numerals in all of the figures of the drawing designate like parts.

The preferred form of the device is shown 40 in Figures 1 to 3 inclusive, and consists of a smoke-storage tube 10 which is preferably conical in shape forming a relatively wide mouth at one end and a relatively narrow mouth at its opposite end, for a purpose 45 hereinafter set forth. A mouth-piece 11 is provided which is also preferably conical in shape and of a greater pitch than is the tube 10, so that its smaller end can be inserted in either mouth of the storage tube to enable 50 the user to blow large or small rings as desired. This mouth-piece is made separable from the tube 10, not only for the purpose of securing the adjustment to either end, but also to facilitate the packing of the device 55 for shipment, as numbers of each of the conical members can be nested within each

other, thereby making small packages and prevent the destruction of the toys during shipment.

In practical operation the mouth-piece is 60 placed against the outside of the lips of the user after he has drawn a full mouthful of smoke from a cigar or pipe, and then by emitting short puffs the smoke-rings will be blown from the opposite end after sufficient 65 smoke has accumulated in the storage tube. Or the user can retain his pipe or cigar in his mouth and place the mouth-piece alongside of the cigar, and as he draws from the cigar he can puff through the blower, and 70 thus form rings while the cigar or pipe is in his mouth.

It has been found by practice, that with the parts assembled as shown in Figure 1, that relatively large rings will be formed 75 at the small end, and when the mouth-piece is adjusted to the small end, as shown in Figure 3, relatively small rings will be blown. It is understood that the mouth-piece will be frictionally held in the ends 80 of the storage tube.

In the modified form shown in Figure 4, the mouth-piece 12 is permanently secured in place by solder, glue or otherwise, depending upon the kind of material that the 85 device is made, either paper, pasteboard, thin metal, or other thin material.

In the construction shown in Figure 5, the ends of the storage tube forms the mouth-pieces, and a disk 13 is frictionally 90 positioned within the storage tube, said disk being provided with a central opening 14 and which serves the same purpose as the small ends of the mouth-pieces heretofore described.

Figure 6 form shows a straight storage-tube 15 and a flaring or conical mouth-piece 16, the flaring mouth-piece in every instance forming a convenient means to place against the lips of the user.

The device is especially adapted for advertising purposes. When made of paper or like material the advertisements can be printed directly upon the material of which the device is made of, and when constructed 105 of metal, labels can be pasted thereon containing the advertisements, or the metal can be stamped with impressed letters, or the proper wording can be stencilled thereon.

Having thus fully described the invention, 110 what is claimed is:—

1. A smoke ring blower, comprising a

smoke storage tube, a mouth-piece conical in shape positioned in one end of the storage tube with its smaller end lying within the same to form a small blow opening within the tube, and with the larger end of the mouth-piece lying outside of the storage tube to form a flaring mouth-engaging portion adapted to fit over the lips of the user.

2. A smoke ring blower, comprising a

conical smoke storage tube, and a conical mouth-piece constructed separately therefrom and adapted to be fitted into the mouth of either end of the storage tube to form smoke-rings of different sizes and also form a flaring mouth-piece for the user.

In testimony whereof I affix my signature.

RICHARD TOENNES.
